United States Patent Office

Des. 213,001
Patented Dec. 24, 1968

213,001

FOOTLET

Harold E. Clayton, Jr., 2 Fairbanks Road,
Chelmsford, Mass. 01824

Filed Nov. 6, 1967, Ser. No. 9,271

Term of patent 14 years

(Cl. D2—329)

Fig. 1.

Fig. 2.

Fig. 3.

FIG. 1 is a side elevational view of a footlet showing my new design, the broken line showing of a foot form being for purposes of illustration;

FIG. 2 is a bottom plan view thereof; and

FIG. 3 is a side elevational view of the design shown in FIG. 1 as it appears in a relaxed and flattened position.

I claim:

The ornamental design for a footlet, as shown and described.
